UNITED STATES PATENT OFFICE

MATTHEW W. RYAN, OF FREEPORT, NEW YORK, ASSIGNOR TO MATTHEW W. RYAN SONS & CO., INC., OF NEW YORK, N. Y.

DESIGN FOR A TEXTILE FABRIC

Application filed January 6, 1931. Serial No. 38,209. Term of patent 3½ years.

To all whom it may concern:

Be it known that I, MATTHEW W. RYAN, a citizen of the United States, residing at Freeport, Long Island, in the county of Nassau, in the State of New York, have invented a new, original, and ornamental Design for a Textile Fabric, of which the following is a specification; reference being had to the accompanying drawing, forming part thereof. The figure is a plan view of the cloth, showing my new design.

I claim:

The ornamental design for a textile fabric as shown.

MATTHEW W. RYAN.
